United States Patent Office

Des. 200,371
Patented Feb. 16, 1965

200,371

DISPLAY BIN

George Gavora, % Maize Industries, Earlyville, Ill.

Filed Oct. 1, 1963, Ser. No. 76,816

Term of patent 14 years

(Cl. D80—9)

Fig. 1

Fig. 4

(Fig. 2)

(Fig. 3)

FIG. 1 is a perspective view of a display bin embodying my new design;

FIG. 2 is a side elevational view thereof;

FIG. 3 is an end elevational view thereof; and

FIG. 4 is a perspective view of a modified form of the bin shown in FIG. 1.

The top of my design is plain and unornamented. The rear side of the modified form of my design is also plain and unornamented.

I claim:

The ornamental design for a display bin, substantially as shown and described.
